US00D756776S

(12) **United States Design Patent**
Orset

(10) **Patent No.:** **US D756,776 S**
(45) **Date of Patent:** **** May 24, 2016**

(54) **BOTTLE CAP**

(71) Applicant: **CELGENE CORPORATION**, Summit, NJ (US)

(72) Inventor: **Frederic Eugene Lucien Orset**, Habere-Lullin (FR)

(73) Assignee: **Celgene Corporation**, Summit, NJ (US)

(**) Term: **14 Years**

(21) Appl. No.: **29/502,015**

(22) Filed: **Sep. 10, 2014**

(51) LOC (10) Cl. **09-07**

(52) U.S. Cl.

USPC **D9/452**

(57) **CLAIM**

The ornamental design for a bottle cap, as shown and described.

DESCRIPTION

FIG. 1 is a top and first side perspective view of a bottle cap showing my new design;

FIG. 2 is a bottom and first side perspective view thereof;

FIG. 3 is a first side elevational view thereof;

FIG. 4 is a second side elevational view thereof;

FIG. 5 is a third side elevational view thereof;

FIG. 6 is a fourth side elevational view thereof;

FIG. 7 is a top elevational view thereof;

FIG. 8 is a bottom elevational view thereof;

FIG. 9 is a top and first side perspective view of a second embodiment of a bottle cap showing my new design;

FIG. 10 is a bottom and first side perspective view thereof;

FIG. 11 is a first side elevational view thereof;

FIG. 12 is a second side elevational view thereof;

FIG. 13 is a third side elevational view thereof;

FIG. 14 is a fourth side elevational view thereof;

FIG. 15 is a top elevational view thereof; and,

FIG. 16 is a bottom elevational view thereof.

In the drawings, the broken lines depict environmental subject matter only and form no part of the claimed design.

1 Claim, 6 Drawing Sheets
